UNITED STATES PATENT OFFICE.

HOWARD E. RICHARDS AND ROBERT H. RAMSAY, OF BELLEVUE, OHIO.

FUSE-BOX.

No. 824,884.

Specification of Letters Patent

Patented July 3, 1906.

Application filed May 15, 1905. Serial No. 260,482.

To all whom it may concern:

Be it known that we, HOWARD E. RICHARDS and ROBERT H. RAMSAY, citizens of the United States, residing at Bellevue, in the county of Huron and State of Ohio, have invented certain new and useful Improvements in Fuse-Boxes; and we do declare the following to be a full, clear, and exact description of the invention, such as will enable others skilled in the art to which it appertains to make and use the same.

Our invention relates to improvements in combination fuse-boxes for use on primary or secondary electric wires, transformers, junction-boxes for branch lines, street-railways and their equipments, and all pole-works.

The objects of our invention are the protection of life and property, the provision of a quick and safe method of replacing a blown fuse, and the assistance of electricians or linemen on dark, stormy, rainy, or sleety nights in closing and opening a circuit without danger of an electric shock and without danger of burning or blinding caused by an arcing fuse.

The above and other objects, which will appear as the nature of our invention is better understood, are accomplished by means of the construction illustrated in the accompanying drawings, in which—

Figure 1 is a front elevation of a fuse-box constructed in accordance with our invention, the cover or lid of the same being swung to its open position. Fig. 2 is a longitudinal sectional view taken on the line 2 2 in Fig. 1. Fig. 3 is a transverse sectional view taken on the line 3 3 in Fig. 2, and Fig. 4 is a view of a slightly-modified form of the invention.

Referring to the drawings by numeral, 1 denotes a suitable box or casing having a hinged cover or lid 2 and within which is mounted our improved multiple fuse cut-out 3. The latter comprises a base 4, constructed of slate or other suitable non-conducting material and secured within the box or casing 1 by screws or other suitable fastening means. Adjacent to one end of the base 4 upon its outer face is secured by screws or other suitable fastening means 5 a transversely-extending terminal bar 6, which has an angularly-disposed end 7, recessed to receive an electric terminal or wire, which is passed through an insulator 8, of porcelain or vulcanized rubber, provided in one side of the box 1. A binding-screw 9 is provided in the recessed portion 7 of the terminal bar 6, so as

to retain the electric wire or conductor therein. Suitably secured at the opposite end of the base 4 is a block 10 to receive the other electric terminal or conductor, which passes through an insulator 11, also mounted in one side of the box or casing. The latter terminal or conductor is adapted to be secured in a recess or opening 12, formed in the block 10, by a binding-screw 13, as clearly shown in Fig. 2 of the drawings.

Pivotedly mounted upon the top of the terminal block 10 by means of a screw 14 is a knife-switch 15, which has upon one of its ends a vulcanized or insulated handle 16. This handle is adapted to project through a slot 17, formed in the bottom or end of the box or casing. The opposite end 18 of the knife-switch is adapted to be swung or moved into contact with any one of a segmentally-arranged series of electrical contacts 19, which are in the form of spaced jaws, of brass or other suitable metal, riveted, welded, or otherwise secured or formed upon spaced fuse-blocks 20, which are preferably formed of copper and screwed or otherwise secured upon the central portion of the base 4.

In Figs. 1, 2, and 3 of the drawings we have shown three of the fuse-blocks 20; but it will be understood that any desired number may be provided. They are electrically connected to the terminal bar 1 by fuse-wires 22, which may be of any form and construction. As shown, these fuses 22 are secured to the bar 6 and the blocks 20 by binding-screws 23 and washers 24. In order to secure a more perfect electrical connection between the terminal block 10 and the knife-switch 15, the end 18 of the latter is connected by a coiled wire 25 to said block 10, as clearly shown in Fig. 2 of the drawings. The coil in the wire 25 permits the lever to be swung to move its end 18 into engagement with any pair of contact-jaws 19, the space between these pairs of jaws being such that the lever cannot be in contact with two pairs at the same time. It will be seen that when one of the fuses 22 is blown by the passage of an abnormal current therethrough the line or circuit may be quickly, easily, and safely closed by swinging the lever into engagement with one or the other of the pairs of jaws 19. In order to prevent the blowing of one fuse from injuring the others, webs or partitions 26 of any suitable insulating material are provided upon the base 4 between said fuses, as shown in the drawings.

In Fig. 4 of the drawings we have shown a form of the invention adapted for use on secondary lines. The intermediate pair of contact-jaws 27 is used to hold the lever 15 when it is desired to cut off the current or circuit, and its block is not connected by a fuse to the terminal bar 6. The fuse-wires 28 and 29, which connect the two outer fuse-blocks to the terminal bar, are shown in this form of the invention of different sizes—that is, of different amperage capacity—so that the device may be adapted for different kinds of current by shifting the knife switch or lever. In this form of the invention the terminal or conductor socket 7 instead of being at one end of the bar 6 is formed at the center of its top, as shown at 30.

The construction, use, and advantages of our invention will be readily understood from the foregoing description, taken in connection with the accompanying drawings. It will be seen that owing to the fact that the device is entirely inclosed by the casing or box 1 no danger to person or property can be caused by the blowing of one of the fuses and that a blown fuse may be quickly and safely replaced by simply shifting the insulated handle 16 of the switch-lever. The device reduces to a minimum the risks or dangers that electricians or linemen are subjected to in replacing fuses in other devices of a similar nature in hazardous places or on dark and stormy nights. When one fuse is blown, it may be removed and replaced by a new one with little danger while the circuit is completed through one of the other fuses.

While we have shown and described the preferred embodiment of our invention, it

will be understood that we do not wish to be limited to the precise construction herein set forth, since various changes in the form, proportion, and the minor details of construction may be resorted to without departing from the principle or sacrificing any of the advantages of this invention.

Having thus described our invention, what we claim as new, and desire to secure by Letters Patent, is—

A device of the character described comprising a box or casing having a removable cover, a base of non-conducting material within said casing, a terminal bar secured adjacent to one end of said base, a terminal block secured adjacent to the opposite end of said base, insulators in said casing to receive the terminals of electrical conductors, a knife-switch pivoted upon said block, an insulated handle upon said switch projecting through a slot in said casing, a flexible conductor-wire connecting said block and said switch, a series of fuse-blocks secured upon said base, segmentally-arranged contact-jaws upon said fuse-blocks adapted to be engaged by said knife-switch, and binding-screws for securing the ends of fuse-wires to said terminal bar and to said fuse-blocks, substantially as described.

In testimony whereof we have hereunto set our hands in presence of two subscribing witnesses.

HOWARD E. RICHARDS.
ROBERT H. RAMSAY.
